ATTORNEY

UNITED STATES PATENT OFFICE.

GOZO KAWAMURA, OF NEW YORK, N. Y.

NAIL PULLER.

Application filed January 13, 1922. Serial No. 528,899.

To all whom it may concern:

Be it known that I, Gozo KAWAMURA, a subject of the Emperor of Japan, residing at New York, in the county of New York and 5 State of New York, have invented certain new and useful Improvements in Nail Pullers, of which the following is a full, clear, and exact description, such as will enable others skilled in the art to which it appertains to make and use the same.

This invention relates to pulling implements and, with respect to its more specific features, to instruments for extracting nails, spikes or similar objects.

15 An object of the invention is to provide a powerful and simple tool which will extract nails of a great variety of sizes.

Another object is to provide a nail extractor which may be used with a minimum of 20 damage to the wood or other material in which the nail is embedded.

Another object is to provide a construction for a nail extractor which will produce little or no deformation of the nail.

25 Another object of the invention is to provide a tool of this character which is simple and positive in action and easily handled.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the following claims.

One embodiment which the invention may assume in practice is shown in the drawings which include—

40 Figure 1, which is a plan of the implement;

Fig. 2, a side elevation showing details of the nail lifting member;

Fig. 3, a cross sectional view taken 45 through the nail lifting member;

Fig. 4, a cross sectional view showing a nail in position within the lifting member;

Figs. 5, 6 and 7, showing the manner in which the extractor is employed to pull a 50 nail; and

Fig. 8, which shows a modified form of the nail lifting member.

In the various figures similar reference characters relate to similar parts.

55 In carrying out the invention the implement is constructed from a round metal bar

or shaft 1, bent at one end to form lifting member 2 and at the other end to form lifting member 3. Lifting member 2 lies in a plane at right angles to lifting member 3. 60 Both lifting members 2 and 3 are bent to an angle greater than 90 degrees with the shank of the bar 1 for reasons which will become evident from the description of the manner in which the instrument is employed. The 65 nail or similar article which is to be extracted by this instrument is pulled by the ends of lifting members 2 and 3, and for this purpose the ends of these members are hollowed or chambered to form a longitudinal recess 70 5 which is larger than the head of the largest size nail which the instrument is designed to pull. On the outer side of lifting member 2 there is cut a slot 6 extending 75 from its outer surface to the recess 5 and having sharp cutting edges 8. The faces 7 of slot 6 flare outwardly so that the edges or jaws 8 project toward each other, in position to cut into the shank of a nail when inserted therein. The slot for receiving the 80 shank of a nail may be formed as shown in Fig. 2, wherein jaws 8 taper very slightly; or it may be of the form as shown in Fig. 8 wherein the slot 10 is of triangular form, which adapts the instrument for use with a 85 greater variety of sizes of nails. The tip of lifting member 2 is ground to a sharp cutting edge 4, the purpose of which will be described hereinafter. The outer portion of lifting member 2 is flattened at the groove 90 6, to provide a face 11 whereby the tool is made thinner at the point where it is to be inserted under the head of a nail, facilitating its insertion thereunder. Lifting member 3 is constructed similar to lifting member 2, but preferably of different proportions, adapting it to be used with a different range of sizes of nails. A convenient arrangement is to construct lifting member 2 with jaws as shown in Fig. 2, and lifting member 3 with jaws as illustrated in Fig. 8. 95 Assuming that a nail 12 is to be extracted from a wooden member in which it is embedded, that end of the tool which fits the nail 12 more closely is placed on the wood 100 so that the sharp edge 4 encircles the head of nail 12. A blow of a hammer upon the face 9, located approximately at the bend of bar 1, forces the round cutting edge 4 of the tool into the wood. The wood fibres are 105 thus cut in a ring which prevents the lifting of splinters from the wood by the operations 110

following. The tool is then raised gradually and subsequent hammer blows on face 9 drive edge 4 of the tool toward and under the head of nail 12, so that the recess 5 receives the head of the nail and slot 6 receives its shank. The lifting member 3 of the tool is then raised still more to a position in which the bottom face 11 of the lifting member 2 rests upon the wood, and, with the 10 bend in the shank of the tool acting as a fulcrum, the nail is easily extracted by pressure exerted on lifting member 3. When the nail to be extracted has a small head like a finishing nail, or none at all, it is desirable to 15 give an extra blow of the hammer on striking face 9 when the tool has been raised nearly to the drawing position. This causes the sharp edges 8 of the slot 6 to bite into the shank of the nail and hold it firmly 20 while being pulled.

Since lifting member 3 is in a horizontal position during the pulling operations, it serves as a convenient handle, making it possible to exert great force upon the nail, 25 and prevents the tool from turning sidewise as it is pulled.

The sharpened edges 4 of the tool serve to make the damage to the wood very slight, while inserting the tool under the head of the nail, so that boards, planks or the like, from which nails have been drawn may be 30 readily used again. Sharpened edges 4 also assist in engaging the nail by cutting a passage to ease the jaws into gripping position.

The length of the lifting members 2 and 35 3 should be made substantially as long as the longest nail which the tool is to pull. This enables the tool to draw any nail up to that length with little or no bending, since 40 the tool is then turned through a circular arc of only about 60 degrees. Nails so pulled may be used again without the necessity of straightening.

With a tool constructed as above described all sizes of nails having shanks which may be received in the slot 6 or 10, as the case may be, may be easily extracted,

since there is enormous leverage provided in the proportionate lengths of the shank of bar 1 and the lifting members 2 and 3. The 50 proportions of the instrument may be varied to pull any size of nail or spike.

As many changes could be made in the above construction and many apparently widely different embodiments of this invention could be made without departing from the scope thereof, it is intended that all matter contained in the above description or shown in the accompanying drawings shall be interpreted as illustrative and not 60 in a limiting sense.

It is also to be understood that the language used in the following claims is intended to cover all of the generic and specific features of the invention herein described, 65 and all statements of the scope of the invention which, as a matter of language, might be said to fall therebetween.

Having described my invention, what I claim as new and desire to secure by Letters 70 Patent is:

1. A nail puller including a shaft having, on each end, a lifting arm extending at a substantial angle to said shaft, said shaft and one of said arms lying in a plane at an 75 angle to that in which said shaft and the other said arm lies, each of said arms having a nail extracting device.

2. A nail puller including a shaft having, on each end, a lifting arm extending at a substantial angle to said shaft, said shaft and one of said arms lying in a plane at an angle to that in which said shaft and the other said arm lies, each of said arms having a nail extracting device, including a circular cutting end and a longitudinal outwardly flaring slot for reception of the 80 shank of the nail.

In testimony whereof I affix my signature, in the presence of two witnesses.

GOZO KAWAMURA.

Witnesses:

JEANNIE W. DARLING,
M. A. CASHIN.
